H. T. SHEARER.

INTERNAL GRINDING WHEEL BEARING.

APPLICATION FILED OCT. 11, 1910. RENEWED SEPT. 29, 1913.

1,078,560.

Patented Nov. 11, 1913.

UNITED STATES PATENT OFFICE.

HARRY T. SHEARER, OF WAYNESBORO, PENNSYLVANIA; ASSIGNOR TO LANDIS TOOL COMPANY, OF WAYNESBORO, PENNSYLVANIA, A CORPORATION OF PENNSYLVANIA.

INTERNAL-GRINDING-WHEEL BEARING.

1,078,560.

Specification of Letters Patent. Patented Nov. 11, 1913.

Application filed October 11, 1910, Serial No. 586,579. Renewed September 29, 1913. Serial No. 752,481.

To all whom it may concern:

Be it known that I, HARRY T. SHEARER, a citizen of the United States, residing at Waynesboro, in the county of Franklin and State of Pennsylvania, have invented certain new and useful Improvements in Internal-Grinding-Wheel Bearings, of which the following is a specification.

In the use of grinding wheels on grinding machines for internal grinding, considerable trouble has been experienced in providing a support for the outer end of the grinding wheel spindle that will hold said grinding wheel steady and avoid "chatter", or vibration. This is especially true after the bearing has become worn.

The object of my said invention is, therefore, to provide a bearing for the outer end of the grinding wheel spindle of internal grinding fixtures for use on grinding machines, which will afford a bearing that will hold the spindle to run true and steady, and that may be adjusted to maintain a close bearing and steady support at all times, all as will be hereinafter more fully described and claimed.

Referring to the accompanying drawings, which are made a part hereof and on which similar reference characters indicate similar parts, Figure 1 is a top or plan view of an internal grinding fixture for use on grinding machines embodying my said invention, Fig. 2 a central longitudinal section through the same, Fig. 3 an end elevation, and Fig. 4 a cross section on the dotted line 4-4 in Fig. 2.

In said drawings the portions marked A represent the base of the fixture, B a bearing supporting tube or sleeve and C the grinding wheel spindle.

The base A is a casting of a usual, or any appropriate form, adapted to be secured to the grinding wheel base by means of bolts inserted through the slots a, as is usual. It is formed with a transverse bore to receive and support the bearings for the grinding wheel spindle. Its outer edge is split and connected by screws 10, 11, 12 and 13 which extend across the split through a perforation in the projecting top flanges, or ears, a', and into a screw-threaded perforation in the lower flanges, or ears, a'', as best shown in Fig. 3.

The sleeve B is formed at its inner end

of a size to fit within the bore of the base A 55 and is securely clamped by the clamping screws 10 and 11. The inner end of said sleeve is screw-threaded and a threaded thimble B' is mounted therein formed with a flange b on its outer end. Said flange b 60 is formed with a notch, or notches, 14, in its periphery adapted to engage with a pin 15 which is mounted in a perforation in the base A and projects into the interior of the bore to engage said notch and hold said 65 thimble from rotation. Said sleeve B is of a length to extend outward the distance from the base necessary to project into the work as required and afford a bearing for the spindle close to the grinding wheel. 70 The outer end of its bore is formed slightly flared, or of increasing diameter from a point back from its end, as at a point marked x, to its outer end. In this portion is mounted a split bushing 16 the outer surface of which is correspondingly tapered to fit within the outer end of said sleeve. Said bushing is of bronze, or other appropriate material, adapted to furnish a suitable bearing for the outer end of spindle C, which 80 fits snugly therein. Said spindle C has the grinding wheel c mounted on its outer end, said wheel preferably secured on a base C' which has a rearwardly extending annular flange c' projecting back over the outer end 85 of sleeve B to protect the joint between said spindle and the bushing 16. Said grinding wheel is clamped to the end of the spindle by means of a screw 17 projecting through a plate 18 on its outer end and into a screw-threaded perforation in the end of said spindle. A distance tube 20 is interposed between the inner end of bushing 16 and the adjacent end of thimble B' to hold said bushing when sleeve B is backed on said 95 thimble and thus force said bushing out of said sleeve. Said spindle is preferably formed in two parts, the rear end C² being connected to the front end C by a socket c² on the rear end of said part C into which 100 the front end of the part C² is inserted, said front end of part C² being formed with a transverse notch which embraces a pin c³ extending transversely through said socket. Bearing blocks C³ and C⁴ are mounted in 105 the bore in the base A in which said part C² is journaled, a pulley C⁵ being mounted between said bearings for the driving belt.

Suitable oil cups are shown, and other details of construction and arrangement, but not particularly described, being common in this class of devices and readily understood 5 from the drawing.

In use, the parts being adjusted as shown in Fig. 2, and the bearing in the bushing 16 becoming loose by wear, the operator loosens clamp screws 10 and 11 sufficiently 10 to permit sleeve B to be turned therein. He then seizes said sleeve around the knurled portions b' and turning it on the thimble B' forces it outwardly over the split bushing 16 compressing said bushing tightly upon 15 the outer end of spindle C. He then gives said sleeve a backward turn, sufficient to relieve the bushing from a clamping hold upon the spindle but still holding it in close turning relation thereto. This may loosen 20 the end bearing between the end of sleeve 16 and inner face of base C', but a slight forward turn will adjust the parts again so that the end thrust of the spindle between base C' and washer c' will permit no lost 25 motion or reciprocal vibration. The clamping screws 10 and 11 are then tightened and the work proceeds. By this construction and in the manner described, from time to time, the bearing is tightened, or closed up, 30 to keep the parts in close relation and prevent vibration, thus prolonging the life of the bearing and securing accurate and true grinding at all times. The bearing being close to the grinding wheel said wheel is 35 given a firm support and being a snug running bearing at all times the wheel is held from vibration and perfect results are secured. When it is desired to loosen the bearing, it can be readily done by reversing the 40 operation above described, that is, loosen the clamp screws 10 and 11 and back the sleeve B off bushing 16, tube 20 holding said bushing outward as said sleeve turns back thus

permitting said bushing to expand and the bearing to loosen as much as desired. 45

Having thus fully described my said invention, what I claim as new and desire to secure by Letters Patent, is:

1. The combination with an internal grinding fixture for grinding machines, of 50 the base, a sleeve adjustably held in said base on a screw-threaded thimble, means for holding said thimble, means for clamping said sleeve rigidly in said base, a bushing mounted in the outer end of said sleeve, said bushing and sleeve being formed with engaging tapered faces, a grinding wheel spindle mounted within said sleeve and journaled at its outer end in said bushing, and at its inner end extending through said 55 thimble, and the grinding wheel mounted on the outer end of said spindle, substantially as set forth.

2. The combination in an internal grinding fixture for grinding machines, of a bearing supporting sleeve with a thimble screw-threaded into its inner end, means for locking said thimble, means for clamping said sleeve, a bushing mounted in the outer end of said sleeve by a tapered engagement, a 60 grinding wheel spindle mounted within said sleeve with its outer end journaled in said bushing, a grinding wheel mounted on the outer end of said spindle with its base bearing against the outer end of said bushing, and a distance tube between the inner end of said bushing and the adjacent end of said 65 thimble, substantially as set forth.

In witness whereof, I, have hereunto set my hand and seal at Waynesboro, Pennsylvania this 28th day of September, A. D. nineteen hundred and ten.

HARRY T. SHEARER. [L. S.]
